UNITED STATES PATENT OFFICE.

ARTHUR E. PALMER, OF CLEVELAND, OHIO, ASSIGNOR, BY MESNE ASSIGNMENTS, TO THE STANDARD PARTS COMPANY, OF CLEVELAND, OHIO, A CORPORATION OF OHIO.

CHARGE-FORMING DEVICE FOR EXPLOSION-MOTORS.

1,254,348.

Specification of Letters Patent. Patented Jan. 22, 1918.

Application filed April 28, 1914. Serial No. 835,032.

To all whom it may concern:

Be it known that I, ARTHUR E. PALMER, a citizen of the United States, and a resident of Cleveland, county of Cuyahoga, and State of Ohio, have invented a new and useful Improvement in Charge-Forming Devices for Explosion-Motors, of which the following is a specification, the principle of the invention being herein explained 10 and the best mode in which I have contemplated applying that principle, so as to distinguish it from other inventions.

The present improvements relate to charge forming devices for explosion motors, the mechanism involving what is popularly known as a carbureter and being designed to secure an effective vaporization of low grade fuels such as kerosene and the like. To this end means are provided for 20 readily vaporizing the fuel at starting, rendering it unnecessary to provide an auxiliary supply of light fuel, such as gasoline, which is commonly required in the usual type of kerosene carbureters, the 25 aforesaid means being capable of disconnection when the engine is started, at which time the exhaust or waste gases from the motor are utilized for the heating of the fuel in order to effectively vaporize the 30 same. To the accomplishment of these and related ends, said invention, then, consists of the means hereinafter fully described and particularly pointed out in the claims.

The annexed drawing and the following 35 description set forth in detail certain mechanism embodying the invention, such disclosed means constituting, however, but one of various mechanical forms in which the principle of the invention may be used.

40 In said annexed drawing:—

Figure 1 is a vertical section through the improvements constituting my invention; Fig. 2 is a similar view showing a modification of the device; and Fig. 3 is a plan 45 view of a detail of the construction shown in Fig. 1.

In Fig. 1 there is shown a conduit 1 which leads to the cylinders (not shown) of an explosion motor, such conduit being usually 50 referred to as the intake manifold. Connected to the lower end of such conduit is a casing or chamber 2 which serves as a

mixing chamber for the fuel and air, the air being supplied through a nozzle 3 disposed horizontally in one end of the casing 55 2 and being controlled by means of an adjustable needle valve 4. The fuel is supplied to the mixing chamber through a vertically disposed nozzle 5 which is connected by means of a suitable pipe 6 to a float 60 chamber (not shown) of any desired type, which will be disposed so as to maintain the level of the liquid in the nozzle at about the position indicated by the numeral 7.

Mounted about the nozzle 5 and attached 65 to, or formed integral with the casing 2, as may be preferred, is a second or auxiliary casing 8 which is provided with inlet and outlet openings 9 and 10, respectively. The opening 9 is connected with a pipe 11 which 70 will be attached to the exhaust pipe from the motor, thus providing a flow of hot exhaust gas through the casing 8 and around the inlet nozzle 5 when the motor is being operated.

75 Mounted about the adjustable needle valve 4 for the air nozzle 3 is a small casing 12 which is provided with a conduit 13 entering the exhaust pipe 11 but taking air at an end 14 disposed exteriorly of said 80 pipe. In this way the air is heated by means of exhaust after the motor has been started and by thus heating both the air and the liquid fuel a complete vaporization of the latter and a very intimate mixture of the two can 85 be secured, which is of course the result desired in all types of carbureters and particularly in carbureters handling heavy oils where it is difficult to entirely vaporize all 90 of the heavier constituents of the fuel.

An auxiliary air valve 15 is provided in one end of the casing 2, such valve being of a well known type and therefore not requiring a detailed description. It will, of course, be understood that this valve will 95 be held continuously open at high speeds and will be intermittently open at medium speeds, being entirely closed at low speeds, when a rich mixture is desired.

In order to start the motor upon the 100 heavy fuel without using some lighter oil such as gasoline, additional heating means are provided for both the air and fuel, such means preferably taking the form of elec-

trical heating coils 16 and 17 connected in series and disposed respectively about the air pipe 13 and the fuel conduit 5 and being suitably covered to protect the same from the action of the exhaust gas. A switch 18 is provided in the circuit, as well as a source of current 19, which will usually be a battery, as of course this heating means will not be required for more than the few 10 seconds prior to the starting of the motor.

It will be noted that the air nozzle 3 is disposed at substantially right angles to the fuel nozzle 5, the current of air passing across the fuel nozzle and vaporizing the 15 liquid therein. A certain amount of fuel is thus drawn up in the form of minute drops of liquid which would in many cases fall upon the bottom of the casing 2 and not reach the engine cylinders. To prevent this 20 waste, which would affect the character of the mixture, I dispose about the fuel nozzle 5, and below the air nozzle 3, a concave plate 20 which is provided with an aperture 21 fitting snugly about the top of the fuel 25 nozzle. The air entering through the nozzle 3 and carrying with it the fuel in gaseous or liquid form strikes against this plate at a very slight angle, the plate thus catching any of the fuel which is in liquid form and 30 preventing the same from falling to the bottom of the mixing chamber 2. In order to subsequently vaporize this liquid retained on the plate 20, I provide a heating coil 22 connected in series with the heating coils 16 35 and 17.

In some cases, however, it is desirable to form the plate 20 as a part of the top of the chamber 8, as in this construction the exhaust gas serves to maintain the plate at 40 a high temperature at all times, thus entirely eliminating any waste by reason of the collection on this plate of small drops of liquid. Such a modification is illustrated in Fig. 2, in which form the casing 8 is 45 extended up through the casing 2, the top 25 of the casing 8 being curved and acting as does the plate 20 in the construction illustrated in Fig. 1. In this type of my device it is not usually necessary to provide 50 a heating coil about the fuel nozzle proper, the coil 22 serving to sufficiently heat the fuel for starting as the heat is then confined in the casing 8 and is also to some extent directly in contact with the nozzle 5.

55 The present apparatus has been found to efficiently vaporize heavy liquid fuel and mix the same with air without the use of any lighter fuel for starting purposes. The amount of current used for the heating is 60 little as this method is used only until the engine is started.

Other modes of applying the principle of my invention may be employed instead of the one explained, change being made as 65 regards the mechanism herein disclosed, pro-

vided the means stated by any of the following claims or the equivalent of such stated means be employed.

I therefore particularly point out and distinctly claim as my invention:—

1. A carbureter for explosion engines comprising a mixing chamber, an upright fuel nozzle projecting thereinto, a horizontal air nozzle converging to said fuel nozzle, a slightly inclined plate disposed slightly below the level of said air nozzle upon the opposite side of said fuel nozzle, and means for heating said plate. 75

2. A carbureter for explosion engines comprising a mixing chamber, an upright fuel 80 nozzle projecting thereinto, a horizontal air nozzle converging to said fuel nozzle, a slightly inclined plate disposed slightly below the level of said air nozzle upon the opposite side of said fuel nozzle, and means 85 for heating said fuel nozzle and plate and also the air entering said air nozzle.

3. A carbureter for explosion engines comprising a mixing chamber, an upright fuel nozzle projecting thereinto, a horizontal air 90 nozzle converging to said fuel nozzle, a slightly inclined plate disposed slightly below the level of said air nozzle upon the opposite side of said fuel nozzle, and an electric resistance heating element surrounding 95 said fuel nozzle and lying against the bottom face of said plate.

4. Carbureting devices for explosive engines comprising a mixing chamber, a pre-heating chamber, an upright fuel nozzle 100 projecting through said preheating chamber and into said mixing chamber, a horizontal air nozzle converging to said fuel nozzle, a slightly inclined plate disposed slightly below the level of said air nozzle upon the 105 opposite side of said fuel nozzle, and means for simultaneously heating said plate and said fuel nozzle.

5. Carbureting devices for explosive engines comprising a mixing chamber, a pre-heating chamber, conduits leading through said preheating chamber, one of said conduits being for the air and the other for the fuel, said fuel conduit terminating with a nozzle located in said mixing chamber, 110 said air conduit leading to a horizontal air nozzle located in the mixing chamber and converging to said fuel nozzle, a slightly inclined plate disposed slightly below the level of said air nozzle upon the opposite side of said fuel nozzle, and means within 115 said preheating chamber for heating said conduits and means within the mixing chamber for simultaneously therewith heating 120 said plate. 125

6. Carbureting devices for explosive engines comprising a mixing chamber, a pre-heating chamber, conduits leading through said preheating chamber, one of said conduits being for the air and the other for 130

the fuel, said fuel conduit terminating with a nozzle located in said mixing chamber, said air conduit leading to a horizontal air nozzle located in the mixing chamber and converging to said fuel nozzle, a slightly inclined plate disposed slightly below the level of said air nozzle upon the opposite side of said fuel nozzle, and electric resistance heating elements associated with said

conduits and said plate for simultaneously 10 heating the plate and preheating the fuel and the air.

Signed by me, this 18th day of April, 1914.

ARTHUR E. PALMER.
